Des. 231,144
Patented Apr. 2, 1974

231,144

HAIR GROOMING APPLIANCE

Martin J. Wolff, West Haven, Conn., assignor to Sperry
Rand Corporation, Bridgeport, Conn.

Filed Jan. 15, 1973, Ser. No. 323,965

Term of patent 14 years

Int. Cl. D28—03

U.S. Cl. D86—8

Fig. 1.

Fig. 2.

Fig. 3.

FIG. 4.

FIG. 5.

FIG. 6.

FIG. 1 is a front side, top and left end perspective view of a hair grooming appliance, showing my new design;

FIG. 2 is a top plan view;

FIG. 3 is a bottom plan view;

FIG. 4 is a rear side elevational view;

FIG. 5 is a right end elevational view; and

FIG. 6 is a left end elevational view thereof.

I claim:

The ornamental design for a hair grooming appliance, substantially as shown and described.
